LET-OFF MECHANISM FOR LOOMS

Application filed June 11, 1929. Serial No. 370,066.

This invention relates to let-off mechanisms for looms whereby the warp is supplied in proper amount to the weaving instrumentalities.

5 Let-off mechanisms for looms may now generally be classed as of two types, one, known as the "positive" let-off, wherein the warp beam is positively rotated to supply the warp, and the other a friction let-off wherein 10 the warp beam is subjected to means for exerting friction thereon. The present invention is more particularly directed to the positive type of let-off mechanism of the general character now known as the "Roper let-off", as exemplified in the Roper Patent, No. 15 744,941, dated November 24, 1903.

In the so called "Roper let-off" the warp beam is provided with a gear meshing with a pinion fast on a driving shaft, on which later 20 a ratchet is loosely mounted, and motion is transmitted to the driving shaft through a train of speed reducing gearing. The speed reducing gearing comprises an internally toothed gear secured to the driving shaft 25 and meshing with a non-rotatable externally toothed gear of less number of teeth and loosely mounted on an eccentric connected to the ratchet, an arm being employed and connected with the externally toothed gear to prevent its rotation. By reason of the difference in the number of teeth on the two 30 gears, the internally toothed gear will rotate slowly by reason of its engagement with the non-rotatable externally toothed gear as the latter travels within the internally toothed gear and in mesh therewith.

In the practical operation of the "Roper let-off" it has been found that the warp beam slows down and then increases its speed at 40 regular intervals entirely independent of the warp tension or the diameter of the yarn mass on the beam. This irregularity of let-off does not materially produce noticeable effects in a large number of fabrics, but in 45 some of the finer grades objectionable streaks appear in the cloth.

One of the objects of the present invention is to so improve the positive let-off of the Roper type as to entirely eliminate the 50 periodic irregularity in let-off, and consists

in means associated with the speed changing mechanism for producing an even and unvarying rotative movement to the warp beam throughout the loom operation, thereby eliminating any objectionable streaks in the 55 finer grades of fabrics.

The invention and novel features thereof will best be made clear from the following description and the accompanying drawings 60 of one good form thereof.

In the drawings:

Fig. 1 is a side elevation of a loom having a positive let-off provided with the present invention;

Fig. 2 is a sectional rear elevation on an 65 enlarged scale on the line 2—2 of Fig. 1;

Fig. 3 is an enlarged detached detail showing the relation of the internally and externally toothed gears and the gear holder;

Fig. 4 is a section on the line 4—4 of Fig. 3; 70

Fig. 5 is an enlarged section on the line 5—5 of Fig. 2;

Fig. 6 is a face view of the cage containing anti-friction rollers to be interposed between the externally toothed gear and the eccentric 75 on which it is loosely mounted; and

Fig. 7 is an edge elevation of Fig. 6.

The loom frame 1 may be of usual construction for proper support of the operating parts, and the lay 2 is supported by the lay 80 swords 3 mounted for rocking movement on the lay rock shaft 4. The lay is given its beat-up movements through a pitman 5 connected to the crank shaft 6, as usual.

The warp beam 7 is provided with a large 85 gear 8 meshing with a pinion 9 secured to the driving shaft 10, and loosely mounted on the driving shaft is the ratchet 11 which is given its step-by-step movement through a pawl 12 mounted on a pawl carrier 13 which may be 90 conveniently supported upon the driving shaft 10.

Extending downwardly from the pawl carrier 13 is an arm 14 connected to a rod 15 having a slotted end portion 16 embracing a stud 17 on a rocker arm 18 secured to the lay rock shaft. The amplitude of pawl movement is controlled through an arm 19 which bears upon the mass of warp on the warp beam and is pivotally mounted at 20. The arm 21 is connected to a radius arm 22 100

carrying a roller 23 having sliding engagement with the pawl carrier 13 and the pawl setter 24 which is pivotally mounted at 25 (Fig. 1) and connected by a rod 26 to the 5 rocker arm 27 extending from the rock shaft 28, from which project the whip roll carrying arms 29. All of the above parts, including the spring 30 on the rod 26, which is itself connected to the pawl setter arm 24, 10 are or may be of the same general character as more fully described in the Roper patent above mentioned.

Between the ratchet 11 and the driving shaft 10 is the speed reducing mechanism, 15 comprising the eccentric 31 connected to the ratchet 11, and the externally toothed gear 32 loosely mounted on the eccentric and having teeth which mesh with the teeth of an internally toothed gear 33 secured to the 20 driving shaft 10, and these parts as thus far described may be of the same general character as similar parts in the Roper patent.

The internally toothed gear 33 may be secured to the driving shaft 10 by any suitable 25 means, but as herein shown the face of the internal gear is provided with a series of ratchet teeth 34 which are engaged by a detachable finger 35 rising from the hub portion 36 of the finger carrier 37 which is secured 30 to the driving shaft 10 by a bolt 38.

The externally toothed gear 32 which, as previously described, is loosely mounted upon the eccentric 31, is provided with pins 39 on each of which is rotatably supported 35 a roller 40. Each of the rollers 40 extends into a slot 41 of the projecting portions 42 of a gear holder 43, one end of which is provided with a slot 44 embracing the shaft 20, whereby the gear holder may have sufficient 40 longitudinal movement to accommodate the similar but nonrotative movement of the externally toothed gear 32 as it travels about the internally toothed gear 33, and by reason of its less number of teeth imparts slow rotational movement to the gear 33 which is secured to the driving shaft.

From the construction thus far described it will be apparent that the externally toothed gear 32 will be raised by the eccentric during part of the eccentric movement and subsequently lowered as the externally toothed gear partakes of its circular movement within the internally toothed gear. As the externally toothed gear 32 is raised by the eccentric, the weight of the gear and of the 50 projecting portion of the eccentric will cause a retardation to the let-off, and, conversely, when the externally toothed gear 32 moves in a downward direction in its circular path, 55 the weight thereof and of the eccentric contribute to increasing the speed of let-off.

Under the construction thus far described it will be apparent that the unevenness of let-off will be manifested periodically during one cycle of the circular movement of the 60

externally toothed gear, and one of the purposes of the present invention is to provide means for eliminating the unevenness of let-off thus indicated.

As one simple means to this end, the present invention contemplates the provision of a counterbalance associated with the eccentric to compensate for the variation in gravity effect of the eccentric and externally toothed gear during the circular movement 75 of the latter.

To the above end, the present invention provides a weight 45 shown as secured to the ratchet 11 at a point opposed to the high part of the eccentric, with the result that as the eccentric turns and raises the externally toothed gear 32, the weight 45 will be disposed in a diametrically opposite position to the high part of the eccentric, to thereby compensate for the increased weight both of the eccentric and externally toothed gear as they travel upward in the circular path of movement of the gear, and as the eccentric turns to carry the externally toothed gear in a downward direction in its circular path, the weight 45 will act in opposition to the gravity effect of the eccentric and toothed gear.

The weight or counterbalance 45 may be conveniently associated with the eccentric by securing the weight to one of the radial arms 46 of the ratchet 11, as indicated in Figs. 2 and 5, and in order to vary the counterbalancing effect of the weight, it may be adjustably secured in position by means of a slot 47 (Fig. 2) through which is passed 100 a securing bolt 48.

Thus, during the circular movement of the externally toothed gear within the internally toothed gear, all variable tendency for periodic, uneven let-off is eliminated.

As contributing to the evenness of let-off which is primarily furnished by the counterbalance as hereinbefore described, there is interposed between the externally toothed gear 32 and the eccentric 31 a series of anti-friction bearings, consisting, in the present instance of the invention, of a cage 49 (Figs. 6 and 7) containing a series of anti-friction rollers 50 which may be held within the cage by any suitable means, but as herein shown by a spring wire 51.

During the circular movement of the externally toothed gear 32 and its transmission of movement to the internally toothed gear 33, a slight twisting or binding effect may result between the gear holder and the externally toothed gear where the latter is provided with rigid engaging lugs, and such twisting or binding effect is eliminated in accordance with the present invention by the rotatable rolls 40 carried by the pins 39 extending from the face of the externally toothed gear 32.

As shown, the ratchet 11 may be provided with a brake 52 for steadyng the ratchet movement, and such brake may be substan- 130

tially the same as that in the Roper patent hereinbefore mentioned.

What is claimed is:

1. In a let-off mechanism for looms, the combination of the warp beam, a shaft connected to the warp beam to positively rotate it to let-off the warp, a ratchet loosely mounted on the shaft and having an eccentric, an externally toothed gear loosely mounted on the eccentric and held from rotative movement, an internally toothed gear secured to the shaft, and a weight connected to the eccentric for rotative movement therewith to counterbalance the eccentric and externally toothed gear in their movements that the let-off may be rendered uniform throughout the rotation of said shaft.

2. In a let-off mechanism for looms, the combination of the warp beam, a shaft having a ratchet loose thereon, transmitting connection between the shaft and warp beam to effect rotation of the latter, speed reduction gearing between the ratchet and shaft to rotate the shaft and comprising an externally toothed gear mounted loosely and eccentrically on the ratchet, an internal gear in mesh with the externally toothed gear and fast to the shaft, a weight for counterbalancing the externally toothed gear as it is raised and lowered by the eccentric that the let-off may be uniform through a complete circular movement of the externally toothed gear, and means for holding the externally toothed gear from rotation.

3. In a let-off mechanism of the character described, the combination of the warp beam and means for rotating it to positively let-off the warp, including speed reduction gearing comprising intermeshing external and internal gears, an eccentric on which the external gear is loosely mounted, an arm connected to the external gear to hold it from turning, a weight connected to the eccentric to counterbalance the external gear as it travels within the internal gear that the let-off imparted to the warp beam by the internal gear may be uniform throughout the circular bodily movement of the external gear.

4. In a let-off mechanism of the character described, the combination of the warp beam and means for rotating it to positively let-off the warp, including an internally toothed gear, an externally toothed gear intermeshing therewith, a rotary eccentric on which the externally toothed gear is loosely mounted, anti-friction bearings between the eccentric and externally toothed gear, a weight connected to the eccentric to counterbalance the externally toothed gear as it travels within the internally toothed gear that the rotation imparted to the warp beam to let-off the warp may be uniform throughout the movement of the externally toothed gear.

5. In a let-off mechanism of the character described, the combination of the warp beam

and means for positively rotating it to let-off the warp, including an internally toothed gear and driving connections between it and the warp beam, an externally toothed gear intermeshing therewith, a rotary eccentric on which the externally toothed gear is loosely mounted, a counterbalance for the externally toothed gear and eccentric and acting at the low side of the eccentric, a gear holding arm having side projections provided with slots, pins extending from the face of the externally toothed gear, and anti-friction rolls mounted upon the pins for rotative movement and extending into the slots of the gear holding arm.

6. In a let-off mechanism of the character described, the combination of the warp beam and means for positively rotating it to let-off the warp, including an internally toothed gear and driving connections between it and the warp beam, an externally toothed gear intermeshing therewith, a rotary eccentric on which the externally toothed gear is loosely mounted, a counterbalance for the externally toothed gear acting at the low side of the eccentric, anti-friction bearings between the eccentric and the loosely mounted externally toothed gear, a gear holding arm having side projections provided with slots, pins extending from the face of the externally toothed gear, and anti-friction rolls mounted upon the pins for rotative movement and extending into the slots of the gear holding arm.

7. In a let-off mechanism of the character described, the combination of the warp beam and means for positively rotating it to let-off the warp, including an internally toothed gear and driving connections between it and the warp beam, an externally toothed gear intermeshing therewith, a rotary eccentric on which the externally toothed gear is loosely mounted, a gear holding arm having side projections provided with slots, pins extending from the face of the externally toothed gear, anti-friction rolls mounted upon the pins for rotative movement and extending into the slots of the gear holding arm, and a weight connected to the eccentric and acting at the low side thereof to counterbalance the externally toothed gear as it travels within the internally toothed gear that the rotation imparted to the warp beam to let-off the warp may be uniform throughout the circular movement of the externally toothed gear.

8. In a let-off mechanism for looms, the combination of the warp beam having an attached gear, a pinion shaft having a pinion in mesh with said gear, a ratchet loosely mounted on the pinion shaft and having an attached eccentric, an externally toothed gear loosely mounted on the eccentric, an internally toothed gear secured to the pinion shaft, an arm connected to the externally toothed gear to prevent rotation thereof, and a weight connected to the ratchet for counterbalancing the externally toothed gear as it travels with-

in the internally toothed gear that the rotative movement of the warp beam to let-off the warp may remain uniform during the complete circular movement of the externally toothed gear.

5 In testimony whereof, I have signed my name to this specification.

HORACE H. BURDETT.
